Attorney

UNITED STATES PATENT OFFICE.

OLIVER CLARK TERRELL, OF PORTLAND, OREGON.

PARING KNIFE.

Application filed May 8, 1924. Serial No. 711,855.

To all whom it may concern:

Be it known that I, OLIVER CLARK TERRELL, a citizen of the United States, residing at Portland, in the county of Multnomah and State of Oregon, have invented certain new and useful Improvements in a Paring Knife, of which the following is a specification.

This invention relates to paring knives and it consists in the novel features herein-after described and claimed.

An object of the invention is to provide a knife especially adapted to be used for paring fruit or vegetables of globular or substantially conical form and for slicing the denuded bodies into segments or sections and also for coring and pitting fruits. In the operation of paring fruits or vegetables it is desired that the skins be removed completely from the bodies in one continuous ribbon of the same transverse breadth, and of substantially the same transverse thickness. In that the surfaces of fruit and vegetables, irrespective of the general form of their bodies, do not lie in the same arc of curvature, it is a difficult operation to remove the skin in such form of ribbon, with a straight edge knife or with a knife having a curved edge of but one arc of curvature. Therefore, it is the object of the present invention to provide a knife blade which may be conveniently and effectually used for removing the skin in a continuous ribbon of uniform transverse breadth and thickness from the fruit or the vegetables irrespective of the irregularities which might occur in the general geometrical form of the surface of the article.

With this object in view the knife includes a blade having a plane end portion and which merges into an inner portion which is formed with a succession of arcs of different magnitudes. That is to say these arcs are of different degrees of curvature and the individual arcs of the series of arcs increase in magnitude from the plane end portion of the blade toward that end portion thereof upon which the handle is mounted. At a point between the arcuately shaped portion of the blade and the handle, the blade is provided with a bent portion. In use, the bent portion is inserted in the stem depression of the fruit, and the skin is cut whereby the ribbon is started. During the paring operation the fruit is rotated under the respective arcuate portions of the

blade and the cutting of the ribbon is continued until the body of the fruit is completely denuded. The plane end portion of the blade may then be used for dividing the denuded body into segments or sections.

In the accompanying drawings:—

Figure 1 is a perspective view of the paring knife.

Figure 2 is a diagrammatic edge view of a fragment of the blade of the paring knife.

The paring knife comprises a spatulate blade 1 provided at one end with a plane portion 2. The inner end of the plane portion 2 merges into an arcuate portion 3, the arcuate portion 3 merges into an arcuate portion 4 and the arcuate portion 4 merges into an arcuate portion 5. The cords of the arcs 3, 4 and 5 are substantially of the same length. Of the series of arcs the curvature of the arc 3 is least, the curvature of the arc 4 is deeper than the curvature of the arc 3 and the curvature of the arc 5 is deeper than the curvature of the arc 4. Thus the arcs increase in degrees of curvature from the plane portion 2 but as hereinbefore stated the cords of the said arcs are substantially of the same length. The arc 5 merges into an irregular curve 6 which forms one side of an arcuate bend 7 provided in the blade 1. From the bend 7 the blade is continued into a side 8 which is disposed opposite the irregular curve 6 or which is inclined toward the said irregular curve 6. Handle strips 9 are applied to the opposite side of the blade 1 beyond the side portion 8.

In use the bend 7 is inserted in the stem depression of the body, fruit or vegetable, and the said body is turned with relation to the blade in a usual manner. The irregular curved portion 6 removes the skin from the wall of the depression in the body and starts the ribbon. As the flatter portions of the surface of the body are brought toward the blade the body is worked along the blade so that the different arcs 5, 4 and 3 are brought under the skin of the body. Thus the ribbon which is removed from the body will be substantially of the same transverse breadth in that the cords of the arcs 3, 4 and 5 are of the same length and the ribbon which is removed from the body will be of substantially uniform transverse thickness throughout owing to the fact that the arcs 3, 4 and 5 are of different depths. After the body has been completely denuded it

may be cut into sections or segments in a usual manner by using the plane end portion 2 of the blade.

- With the sharp curved edge 7 the eyes may 5 be removed from potatoes and the green circles may be cut out of parsnips and the parts of the cores may be removed from slices of apples, pears and quinces and the like, and without gouging into the fruit. 10 The blade may not only be used for removing the skins from fruit of every description but may be used for slicing the fruit and removing the seed and pits from the slices in an efficient manner. The curves 5, 15 6 and 7, and the side portion 8 of the blade may be used for coring and seeding and for removing the cores and seeds from such fruit as apples, pears, quinces and the like. The curves 6, 7 and 8 may be used to advantage 20 for removing the eyes from potatoes in an efficient manner. The blade may also be used to advantage for slicing and paring such fruit as peaches, plums, prunes, apricots and other fruits preparatory for drying and for 25 removing the pits or seed from such fruit.

Therefore it will be seen that each curve and each straight edge in the knife blade structure may perform its special function and purpose in slicing and paring fruit and vegetables.

30

Having thus described the invention, what I claim is:

1. A paring knife blade having a plane end portion which merges into a series of successive and joined arcuate portions, the 35 cords of each arc of the arcuate portions being of the same length and the arcs gradually increasing in depth from the plane end portion.

2. A paring knife blade having a plane 40 end portion which merges into a series of arcuate portions, the arcs of curvature of the said arcuate portions being of the same length and the arcs of curvature of the arcuate portions being of different depths, and the said arcuate portion merging into a return bend portion having spaced side walls.

45

In testimony whereof I affix my signature.

OLIVER CLARK TERRELL.
